WINDOW CONSTRUCTION

Edmund Peremi, Manhasset, and Louis Toth,
Flushing, N. Y.

Application December 8, 1938, Serial No. 244,592

14 Claims.

(Cl. 189—69)

This invention relates to windows of the swinging sash type. In a preferred form of the invention, it relates to pivoted sashes mounted in the frame by means of pivots located between the ends of the sash. A modified form of the invention includes windows having sashes mounted on pivots or hinges located adjacent one end or side of the sash.

It is an object of the invention to provide a window construction wherein standard sections may be used for the sash and frame and wherein standard sections of the sash and frame may be interchangeably adapted to engage each other from the inside and the outside of the window, depending upon the relation of the particular portion of the window to the pivot.

A further object of the invention is to provide a stay and a sliding shoe construction in which the shoe shall be mounted to slide in the sash member and provide frictional resistance to hold the window in open position.

A further object is to provide various novel shapes of frame and sash rail sections adapted to have resilient weather stripping mounted therein to insure sealing of the windows.

Further objects and advantages will appear from the following description of certain preferred embodiments of the invention and from the drawings appended thereto in which:

Figure 1 is a fragmentary elevation of a portion of a building wall having a window embodying features of a preferred form of the present invention incorporated therein, a portion of the window being broken away;

Figure 2 is a sectional view taken on line 2—2 of Fig. 1, showing generally the method of mounting the sashes in the frame;

Figure 3 is a fragmentary vertical sectional view taken on line 3—3 of Fig. 1 looking in the direction of the arrows, parts being broken away;

Figure 4 is a fragmentary horizontal sectional view taken on line 4—4 of Fig. 1;

Figure 5 is a fragmentary front elevation of a portion of a frame and sash on a considerably larger scale, showing details of the pivoted connection between the jamb and the rail, the sash being shown in open position;

Figure 6 is a view partly in side elevation and partly in vertical section of the parts shown in Fig. 5;

Figure 7 is a horizontal section on line 7—7 of Fig. 6, the sash being in closed position, looking in the direction of the arrows;

Figure 8 is a vertical section on line 8—8 of the Fig. 6;

Figure 9 is a perspective view of a standard frame member and weather stripping of the form used in the window of Figs. 1 to 8;

Figure 10 is a sectional view taken on line 10—10 of Fig. 9 on a smaller scale, looking in the direction of the arrows;

Figure 11 is a perspective view of the sash rail used with a frame member of the form shown in Fig. 9;

Figure 12 is a section on line 12—12 of Fig. 11 on a reduced scale;

Figure 13 is a side elevation of the jamb member, showing the joints between the upper and lower sections thereof;

Figure 14 is a front elevation of a portion of a building wall having a window embodying features of a modified form of the invention;

Figure 15 is a vertical sectional view taken on line 15—15 of Fig. 14;

Figure 16 is a horizontal sectional view taken on line 16—16 of Fig. 14, showing outswinging sashes;

Figure 17 is a horizontal sectional view taken on line 17—17 of Fig. 14, showing the adaptation of this modification to inswinging sashes;

Figure 18 is a vertical sectional view taken on line 18—18 of Fig. 14 showing a cremorne bolt construction;

Figure 19 is a transverse sectional view taken on lines 19—19 of Fig. 18 looking in the direction of the arrows;

Figure 20 is a horizontal sectional view taken on line 20—20 of Fig. 19 looking downward;

Figure 21 is a section taken on line 21—21 of Fig. 19;

Figure 22 is a diagrammatic sectional view on line 22—22 of Fig. 14, showing a stay construction;

Figure 23 is a diagrammatic sectional view on line 23—23 of Fig. 14 showing the casement in open position.

Referring to the drawings in detail and particularly to the construction shown in Figs. 1 through 13, a pivoted window is shown having a frame comprising header 20, sill 21, jambs 22, pivoted sashes 23, and mullions 24. A plurality of sashes may be mounted in the frame on pivots 25 which may suitably be secured in the frame in a manner to be described. The inward and outward movement of the sashes is controlled by the stays 26. It will be seen, that since the sashes are mounted on pivots, the portions of the sashes on either side of the pivot will open in opposite directions to the frame. Thus, in the form shown, referring particularly to Figs. 2 and

6, the upper portion of the sash is inwardly opening, while the lower portion is outwardly opening. The engaging portions of sash and frame are accordingly so formed as to permit this method of window opening while insuring tight weather sealing relation.

The jambs, header, and sill are preferably formed of bars 27 of identical section which may be of any suitable material such as non-corrosive metal and may, if desired be extruded in one piece to the proper shape. For convenience the jamb member only, as shown in Fig. 4 will be described. This member comprises a base portion 28 having flanges 29 and 30 extending outwardly of the window opening, forming an outwardly facing channel, the outside flange 29 forming a pocket for caulking 31. The inner side of the base 28 has flanges 32 and 33 extending therefrom, each of said flanges being set inwardly of the edges of the base 28. Intermediate said flanges 32 and 33 is situated a short rib 34. The outside flange 32 terminates in an inwardly turned lip 35 and the flange 33 has a lip 36, and offset portion 37, and a flange 38 terminating in a striking lip 40 which may suitably be of somewhat heavier gauge for strength and to provide a broader striking face.

Mounted in the frame member is a resilient V-shaped weather sealing member which may suitably be of non-corrosive metal or other suitable durable resilient material. One leg of the V comprises a base 45 which engages the lip 36 and the rib 34, the vertex 46 of the V being held under the lip 35. The other leg of the V, which is preferably somewhat longer than the base comprises a flexible tongue 47 which engages the sash in a manner to be described when the window is closed and is limited in outward movement and guarded from the ingress of dirt and moisture behind it by the striking lip 40 when the window is open. The overhanging striking lip 40 also protects the thin and flexible edge of the tongue from being injured or from causing injury. The jamb member shown in Fig. 4 is arranged to receive the outwardly opening or lower portion of the pivoted sash. To provide for the inwardly opening portion of the sash, it is only necessary to reverse the position of the flanges 32 and 33.

The jamb includes in addition to the member 27 a supporting angle 50, one leg 51 of which engages the base 28 of the member 27 while the other leg 52 extends laterally of the window into the building wall. In the particular construction shown in Fig. 4 a plate 53 extends inwardly of the window from the leg 52 forming a reveal, having a guard 54 for plaster 55 and terminating in a plaster supporting flange 56. The angle iron 57 between the supporting angle and the reveal serves to insure rigidity of construction. The parts may be secured together by any convenient means and it will be understood that the interior finish described is merely optional and may be varied as circumstances may require.

The header comprising a bar 27 of the standard section may be suitably supported by an angle member 60, the member 60 being suitably secured to the lintel 62, which may be of steel or other suitable material. The member 60 includes a base portion 65 which engages the base 28 of the member 27, and a stepped portion 67 terminating in an upwardly extending flange 68. An inwardly extending reveal plate 69, having a plaster guard

70 terminating in a plaster supporting flange 71 may be used in connection with the header.

The sill includes with the standard member 27 an angle 75, one leg 76 of which engages the base 28 of the frame member 27, the other leg 77 of which extends downwardly into the building wall, a member 78, having a portion extending inwardly of the window opening from the leg 77 of angle 75 forming a stool 79, the stool 79 having a downwardly extending portion 80, inset at 81 to provide a securing point for attachment to the building wall by any suitable means such as screws 82. The angle 83 is attached to the angle 75 and the stool and insures that the sill as a whole shall be rigid and strong. The angles 50, 60 and 75 which may be of steel or other strong metal are preferably welded together or otherwise united at the corners of the frame, so as to form a complete rigid outer frame or back.

As can be seen from Figure 4, the standard frame member 27 may be directly applied to the mullion 24. Thus as many windows as are desired may be assembled in a single row in the field during application to a building without modification of the frame members. The mullion comprising a channel shaped member 85 has two lateral offset flanges 86 upon which are mounted the bases 28 of the members 27. The flanges at the inner edges of the member 27, extend to meet the channel member 85 and the flanges extending from the outside edges of the base 28, may suitably be joined by the filler web 87 whereby a rigid hollow mullion is provided. The strength of the mullion may be determined according to the height of the window by varying the depth of the inwardly extending channel 85 which is used to form the mullion.

The bottom sash rail (see Fig. 3) comprises a rectangularly shaped hollow member having pane engaging seat 100, at one side of which extends a flange 101 having an inward lip 102 at its edge adapted to engage the pane 103. At the other side of the seat 100 is an undercut flange 104 adapted to key with the putty and hold the same in place. To assist in holding the pane in place, a pane clip, such as the clip 105 may be employed. The lip 102 has a definite use for glazing purposes; thus 40 the recess formed by the base 100, the flange 101 and the lip 102 may first be filled with glazing compound 106, the pane 103 may then be set against the lip 102 and there will thus be a complete seal between the rail and the pane without exposing any part of the glazing compound 106 on the inside of the window. Furthermore the pane may be set exactly against the flange 102 and its position in the sash easily determined, without squeezing out all of the glazing compound on the 45 inside of the pane as would happen in the case of a straight pane setting flange.

Extending from the pane seat in a direction away from the pane proper are the two side portions 108 and 109 of the rectangular rail, which 50 are joined near their ends by a web 110 constituting the fourth side of the rectangle. Extending from the side 108 is an offset downwardly extending flange 111 which terminates in an inwardly turned striking lip 112 adapted to strike against the outside of the flange 32 of the frame member when the window is closed. The end of the side 109 provides a striking flange 107 for engagement with the flexible tongue 47 of the weather strip and the outer surface of the side 109

provides a striking point for the striking lip 40 on the frame. Thus in the form described, the short striking flange 107 which engages the resilient tongue 41 is seen to be on the inside of the sash, while the longer flange 111 terminating in inwardly turned striking lip 112 is on the outside of the sash.

The top sash rail is similar to the bottom rail, but reversed in position. It comprises a hollow member having a pane engaging flange 120, a putty retaining flange 121 and long and short striking flanges 122 and 123. This rail differs from the bottom rail in that the long striking flange 122 is situated on the inside of the sash while the short striking flange 123 is situated on the outside thereof.

It is to be observed that where a plurality of sashes are mounted in a single frame one of the meeting rail sections 129 may be identical with the heretofore described top rail member, the other of said meeting rail members comprising a rectangularly shaped hollow rail 130 having situated on the pane side thereof a pane engaging flange 131 terminating in an in-turned lip 132 adapted to engage the pane 103 and having on the opposite side of the rail an undercut putty retaining flange 133. The rail member also has a flange 135 terminating in an overhanging lip 136 and a longer downwardly extending offset flange 137 terminating in an inwardly turned lip 138. Situated between the said flanges is a V-shaped resilient weather stripping member, one leg 140 of the V lying against the wall 141 of the rail, the vertex 142 being engaged beneath the lip 136 and the other leg 143 of the V comprising a resilient tongue which is engaged by striking flange 123 when the window is closed and limited in outward movement by the lip 138 when the flange 123 moves out of engagement therewith.

Any suitable locking means may be provided to secure the meeting rails in tight relationship, such as the latch 144 which is described in our copending application Serial No. 243,935 filed December 5, 1938.

As heretofore described in connection with the jambs, the side rails of the sashes on either side of the pivot 25 must have oppositely disposed striking surfaces to provide for outward and inward opening of the sash on either side of the pivot. In Figures 9 through 12 this relation is particularly illustrated both for the jambs and the side rails. It is further seen that one of the side rail members may be identical with the above described top rail member, while the other is similar in cross section to the bottom rail member.

The result may be accomplished in the case of the rail by forming the sash rail section in one piece having flanges extending outwardly, upwardly and inwardly from either side thereof as indicated in Fig. 12 and then by removing one or the other flange as the case may be, or the result may be accomplished by splicing two portions of rail as shown in Fig. 12, the block 150 being preferably included to strengthen and support the splice. In the case of the jamb, a similar procedure may be used, except that where splicing is employed only one section need be provided, as by reversing this section the engaging and striking surfaces for the oppositely disposed sash are presented. It is again preferable to include supporting block 151 in the channel shaped backing of the jamb. As shown in Figs. 11 and 13, the striking flanges are cut

away at the point of mounting to provide for application of the pivots and movement of the sash.

The pivots 25 upon which the sashes are mounted may preferably be located between the top and bottom of the sash or should it be desired to mount the sash to swing horizontally, the pivots will be located in the header and sill. As shown in Figs. 2, 6, 7 and 8 the sash is mounted to swing outwardly at the bottom and inwardly at the top about the pivots 25. Each pivot comprises a pin 155 rigidly mounted in the frame through the supporting block 151 and the jamb base 28. A bushing 156 is preferably rigidly mounted in the hollow sash rail. The pin may preferably be of steel or similar metal and will turn easily in the bushing. While it can be seen that advantage in opening and closing the window will accrue in locating the pivots so that the window is balanced as to upper and lower in-swinging and out-swinging portions, the pivots may, of course, be located in any convenient position.

The window may be limited in outward movement by means of the stay 26 (see Fig. 6). The stay is secured to the frame (see Figs. 5 and 6) by means of the block 160 to which it is pivotally attached by the screw 161.

The stay is pivotally secured to a friction shoe 162 by means of a detachable screw 163, which may be of any convenient form to permit removal so that the window may be opened beyond the fully extended position of the stay.

The shoe 162 rides in the hollow sash rail 35 and thus the sash rail acts as a part of the stay construction and eliminates the heretofore expensive necessity of making a separate item of the stay and mounting it on the sash.

The shoe 162 comprises a rectangularly shaped member having a notch 170 in one side thereof in which a leaf spring 171 is inserted. The spring 171 is adapted to bear against the side of the channel shaped rail member, the amount of the friction exerted between spring 171 and 45 the side of the rail member being adjustable by the screw 172 which bears against it. A fiber block 173 is mounted in the shoe on the side opposite the spring to aid in making good frictional contact between the shoe and the rail.

It will be observed referring to Figures 6 and 11 that the striking flange 107 which normally engages the flexible tongue 41 of the weather strip when the window is closed, is not present on the portion of the sash between the closed 55 position of the brake shoe 162 and the end of the block 160. This is necessary to permit the stay to assume its position between the frame and the sash when the window is closed. However referring to Figure 7, it will be seen that the 60 side of the stay 26, when in closed position, engages the tongue 41 so that there is sealing contact against the tongue for substantially the entire length of the frame.

Referring now to Figs. 14 through 23, a modified form of the invention is shown. This form includes, referring particularly to Fig. 14, a combination window having an upper transom panel 200, a central casement panel 201, and a lower transom panel 202. In the upper transom panel 200 the sashes swing outwardly and upwardly, in the central panel 201, the sashes swing outwardly on the side frame 205 and the mullions 206. In the lower transom panel 202 the sash swings inwardly and downwardly.

Referring particularly to Fig. 15, the upper

transom panel includes bottom, top, and side rails which may be of identical cross section. This standard rail includes, referring to the top rail for convenience, a hollow rectangular portion 210 having a pane seating portion 211 on one side thereof with pane receiving and putty retaining flanges similar to those heretofore described. The hollow member 210 also includes an inside short upwardly extending flange 212 and a longer outside flange 213 which are adapted to engage striking surfaces on the header 214.

The header 214 includes a web 214a having two upwardly extending flanges 215 and 215a, a flange 216 extending downwardly from the inside edge thereof terminating in an inwardly turned striking lip 217, which is adapted to strike against the flange 212 when the window is closed. The flange 216 also has a shoulder 219 near the base thereof for a purpose to be described. Extending downwardly from the outside edge of the header member is a flange 220 having an inwardly turned lip 221 on the end thereof. Extending downwardly from the web 214a intermediate said flanges is a rib 222. Entrapped in the said header member is a resilient V-shaped weather sealing member, one leg of which rests on the shoulder 219 and the rib 222, the vertex of the V being engaged under the inturned lip 221 and the other leg of which forms a resilient flexible tongue 223 which is limited in outward movement when the window is open by the inwardly turned lip 217 and is engaged in sealing weather tight relationship by the flange 212 of the top sash rail when the window is closed. It can be seen that the striking engagement between the flange 213 and the outside of the flange 220, the engagement of the flange 212 with the resilient tongue 223, and the engagement between the lip 217 and the side of the flange 212 results in a three point weather sealing engagement.

The header member is held in position in the frame by the stepped angle member 225 which is secured by any suitable means to the lintel 226. A plaster guard 227 may also be provided and may suitably be secured to the angle member 225. The drip flange 228 may be suitably secured to the angle member 225 and form with the lintel 226 a pocket for caulking 229.

As shown in Fig. 22 the upper transom 200 may suitably be movable in the frame on the hinges 230 which have stationary leaves 231 secured to the top of the frame and movable leaves 232 secured to the top of the sash rail. The outward movement of the upper transom may preferably be limited by stays 234, which are suitably controlled by friction shoes 235, which may be similar in construction to the shoes heretofore described in connection with the preferred form of the invention.

The transom bar 204 includes a shaped member comparable to two of the header members, heretofore described, placed back to back with the flange 215a removed, the flanges 215 being joined to form the web 241. The disposition of weather strip in the two striking portions of the transom bar is identical with that of the header and need not be again described. Integral with the web 241 may be included a drip guard 242 and between the base portions of the sash engaging parts of the transom bar may be situated a steel or other heavy reinforced member 243, which serves to strengthen and render the construction rigid.

The meeting rails of the outwardly swinging

sashes of the panel 201 include a standard sash member 405 comparable to the rail 210 heretofore described, having striking flanges 406 and 407. The rail 408 which meets the rail 405 includes a hollow rectangular portion having pane engaging means on one side thereof and having extending from the inside edge of the opposite side a flange 410 terminating in a striking lip 411, and a flange 412 extending from the outside edge thereof having an inturned undercut portion 413. Intermediate the flanges 410 and 412 are situated flanges 415 and 416. A V-shaped resilient weather stripping member is mounted in the rail 408, one leg of the V 420 resting on the flanges 415 and 416, the vertex 421 of the V being engaged under the in-turned lip 413 and the other leg 422 of the V forming a freely moving tongue which is limited in outward movement when the window is open by the in-turned lip 411 and is engaged in sealing relation by the flange 407 on the rail 405 when the window is closed.

The upper and lower sash bars of the outwardly swinging sashes of the panel 201 as well as the side rails of the panel 201 and the bar 405 for the meeting rail are identical in cross section with the sash bars 244 and 245 and the side rails of the upper transom panel 200 above described. It can accordingly be understood that considerable saving in production cost may be achieved by providing such a standard part.

It further can be seen that the jamb member 270 is identical in cross section with the header 214 and accordingly a single section may be utilized for both of these frame members. The mullion 272 is observed to be identical with the transom bar 204 with the exception that depending upon the height of the sash the reinforcing bar 273 is broadened to provide more support.

It is thus seen that in so far as the outwardly swinging panels are concerned whether they swing outwardly and upwardly or outwardly on hinges mounted upon the jambs, a single sash rail section is necessary, a single section for header and jamb and a single section for the mullion and transom bar.

The jambs of the inwardly opening transom 202 include a channel member 250 having inwardly extending short ribs 251 and 252, and an undercut flange 253. The jamb proper 254 has a short rib 263 and is adapted to interfit with the ribs 251 and 252 and the flange 253 of the member 250. The member 254 includes an outside flange 256 terminating in an inwardly turned striking lip 257 and a shorter flange terminating in an inwardly turned lip 258. A resilient metallic weather strip 259 is concealed in the jamb member with the flexible tongue 260 engaging the flange 257 when the window is open and the flange 261 of the sash when the window is closed. The sash further includes a striking flange 262 and has pane receiving means as heretofore described.

The member 254 is adapted to be joined with a channel shape mullion web 265 to form with a supporting portion, preferably of steel or other hard metal 266, a strong rigid mullion for central support.

The mullion 265 includes two parallel portions 275 and 276 joined by the web 277. The parallel portions are identical in cross section on either side of the web 277 and include short ribs 278 and 279 and an undercut lip 280. The members 281 and 282 which are observed to be identical with the jamb 254 in cross section are adapted

to interfit with either side of the mullion 265 in the manner previously described in connection with the jamb 254.

The top rail 285 of the inwardly opening transom panel includes a rectangularly shaped hollow member having pane engaging means similar to those heretofore described on the lower side thereof and having an inner upwardly extending flange 286 on the upper side.

The transom bar 289 which separates the upper bar 285 of the inwardly opening transom panel 202 and the lower bar 245 of the outwardly opening panel 201 comprises lower and upper channel members 290 and 291. The lower member includes a base portion 295 having a downwardly extending flange 296 adjacent the outer side thereof terminating in an inwardly turned lip 297 and having a short downwardly extending flange 298, an offset portion extending outwardly therefrom having a flange 299 terminating in an inwardly turned striking lip 300 adapted to strike against the side of the hollow rail 285. Intermediate the flanges 296 and 298 is situated a short rib 301. Mounted in the member 290 is a V-shaped resilient weather sealing member having a base portion 302 engaging the ends of the flanges 298 and 301, the vertex 304 of the V being engaged under the in-turned lip 297 and the other leg of the V forming a flexible tongue 306 which is held from outward and downward movement by the inwardly turned lip 300 when the window is open, and which is engaged by the top portion of the rail 285 when the window is closed. Extending upwardly from the base portion 295 are short flanges 310 and 311, the flange 311 being slightly undercut on one side thereof.

The member 291 comprises a channel shaped portion having a base 315 and flanges 316 and 317 extending downwardly from either edge thereof. The flange 316 terminates in an inset dove-tailed groove 318 adapted to engage the undercut flange 311 and the flange 317 terminates in an inset groove 319 which engages the rib 310. It can be seen that a firm connection is thus achieved between the members 289 and 290. Extending upwardly from the inner edge of the base 315 is a flange 325 terminating in an inwardly turned striking lip 326 and having a shoulder 327 adjacent the base 315. Extending upwardly from the outer edge of base 315 is a flange 328 which terminates in an inwardly turned lip 329. Intermediate said flanges 325 and 328 is a short upwardly extending rib 330. A resilient V-shaped weather strip is mounted in the member 291 in the manner previously described in connection with the upper and lower rails of the outwardly extending sashes of the panels 200 and 201. The weather strip and the flanges 325 and 328 are adapted to be engaged by the striking surfaces of the lower rail member 245 of the outwardly swinging sash panels 201.

The inswinging panel 202 includes a lower sash rail comprising the hollow generally rectangular member 335 having upwardly extending pane engaging flanges as heretofore described and having a downwardly extending flange 336 slightly offset from the inner edge thereof and a downwardly extending flange 337 slightly offset from the outer edge thereof terminating in a striking lip 338. Intermediate said flanges is situated a short downwardly extending rib 339 having an outwardly turned lip 340 at the edge thereof. A V-shaped resilient metallic weather

strip is entrapped in said lower sash member, one leg of the V lying against the horizontal portion of said member, the vertex of the V being held under the lip 340 and the other leg 341 of the V extending outwardly toward the inside of the flange 337. The leg or tongue 341 is limited in outward movement relative to the V by the striking flange 338 when the window is open.

The sill engaged by the lower sash rail above 10 described includes a downwardly extending flange 345 which forms with the building wall 346 a pocket for caulking 348. Extending inwardly and upwardly from the flange 345 is the stepped portion 349 having the riser 350 against which the striking flange 338 is adapted to engage when the window is closed. The top of the riser 350 and its inwardly extending step form a corner which engages the resilient tongue 341 of the weather strip when the window is closed. The stepped portion 349 terminates on its inner side in upwardly and downwardly extending flanges 355 and 356 respectively. The flange 355 is adapted to be engaged on its outer side by the downwardly extending striking flange 336. The sill may suitably be supported by angles 360 and stool 361 which may be suitably secured in rigid and strong relation by the small angle 362.

It will be observed that the jamb member 270 (see Fig. 16) may suitably be adapted to form 30 the member 250 (see Fig. 17) which is used in connection with the in-swinging transom panel and further that the mullion 272 may be adapted in the same manner to provide seats for the adaptor members 281 and 282 as illustrated in 35 Fig. 17. It is further seen that the frame members may be constructed to receive outwardly swinging panels, but if desired an adjustment may be made in the field by shortening the flanges 219, 220, and 222 (see Fig. 15) and applying the adaptor members 254 thereto. In like manner the mullion 272 may be transformed into the mullion 265 and the frame thereupon is adapted to receive inwardly rather than outwardly swinging panels.

45 In Figs. 18 through 21, is shown a cremorne bolt which is especially adapted for use in connection with the window of this invention. The bolt includes (see Fig. 18) the identical shaft members 375 and 376 having bolt heads 377 and 378 at the ends thereof which are adapted to be inserted, when the bolt is actuated, in keepers 379 and 380 situated in blocks 382 and 383 which are held in the upper and lower frame members of the panel respectively. The shafts 375 and 376 are inserted in sockets 385 and 386 which are integral with the rack members 381 and 388 actuated by the pinion gear 390 which in turn will be rotated by movement of the handle 391 which extends from the panel on the inner side of the window. The entire bolt, rack and pinion mechanism may be situated in one of the hollow rails of a sash member and accordingly the mechanism is applicable to the meeting rail, having no mullion therebetween. The rack members slide directly against and are guided and held in position by surfaces of the extruded shape forming the meeting rail.

70 Further to aid in locking the window a latch finger 400 mounted to rotate with the pinion 390 is provided, the end 401 of the finger being adapted to engage cam surface 402 and 403 of the keeper 404, the weather strip being cut away so as to fit against the ends of the keeper.

We claim:

1. A window frame member comprising a web

having inside and outside outwardly directed flanges, an outside inwardly directed striking flange having a marginal lip, a longer inside inwardly directed flange having an outwardly directed striking lip, a shoulder formed near the base of said longer inside inwardly directed flange, and a short rib formed on said web between said inwardly directed outside and inside flanges.

2. A window frame member comprising a web having inside and outside outwardly directed flanges, an outside inwardly directed striking flange having a marginal lip, a longer inside inwardly directed flange having an outwardly directed striking lip, a shoulder formed near the base of said longer inside inwardly directed flange, and a short rib formed on said web between said inwardly directed outside and inside flanges, and a V-shaped resilient weather strip carried in said frame member having one leg bearing against said shoulder and said short rib and having the vertex of the V engaged under the marginal lip of said outside inwardly directed striking flange and having the other leg extending diagonally to engage under said striking lip on said longer inside inwardly directed flange.

3. In a window, a frame, swinging sash mounted in said frame, a pair of cooperating members forming parts of said sash and said frame, respectively, adapted to engage in order to seal the window, one of said cooperating members comprising a web having an outside striking flange having a marginal lip, a longer inside flange having an outwardly directed striking lip, and a V-shaped resilient weather strip carried in said cooperating member having one leg supported by said web and having the vertex of the V engaged under the marginal lip of said outside striking flange and having the other leg extending diagonally to engage under said striking lip on said inside flange, and said other cooperating member comprising a bottom wall, a long outside striking flange formed upon said bottom wall adapted to engage said outside striking flange of said first cooperating member when said sash is closed, and a short inside flange formed on said bottom wall adapted to engage the striking lip of the inside flange of said first cooperating member when the sash is closed and adapted to engage and flex the diagonal leg of weather strip when said sash is closed.

4. In a pivoted window construction, a jamb and a sash rail, a pivot joining said jamb and said rail, said jamb and rail having cooperating sealing and striking portions oppositely disposed on either side of said pivot, one of said members having a V-shaped resilient tongued weather strip mounted therein, the other of said members having a flange engaging said tongue when said window is in closed position, the vertex of said V-shaped weather stripping pointing on either side of the weather strip in direction of the opening of the window and the tongue of said weather strip pointing away from the direction of the opening of said window.

5. In a pivoted window construction a frame, a sash and a pivot joining said frame and said sash, said frame including a jamb having oppositely disposed portions on either side of said pivot, resilient tongued metallic weather stripping mounted in said jamb, said sash having a rail having a flange engaging the tongue of said weather strip when the window is closed, said tongue extending on either side of said pivot in

a direction away from the direction in which the window opens.

6. In a window in combination, a frame and a sash, said frame having a sill, said sill comprising an inwardly extending upwardly stepped portion terminating in an inner upwardly extending flange, said sash member including a lower rail having an outside downwardly extending flange having an inwardly turned lip adapted to engage said step portion of said sill, said rail having a downwardly extending inside flange adapted to engage said inner upwardly extending flange of said sill, a downwardly extending flange intermediate said rail flanges, terminating in an outwardly turned lip, a V-shaped resilient weather strip member mounted on said rail, the vertex of the V being engaged under said outwardly turned lip, one leg of said V comprising a free resilient tongue, said tongue being engaged by the top of the said stepped portion of said sill when said window is closed.

7. In a window, a pair of cooperating frame members including a jamb base and a sash receiving adaptor, said jamb base having short inwardly turned flanges and a dove-tail flange and said adaptor having a short outwardly extending flange and a flange adapted to interfit with said dovetailed flange of said jamb base, said adaptor having sash cooperating flanges on its side remote from the jamb base.

8. In a window construction, a frame having a jamb base and an adaptor, said jamb base comprising a web having outside and inside inwardly extending flanges, one of said flanges being undercut, said adaptor having a dove-tail lip engaging said undercut flange of said jamb base, an inwardly extending flange on the outside edge of said adaptor terminating in an inwardly turned striking lip and a shorter inwardly extending flange adjacent the inner edge of the said adaptor terminating in an inwardly turned lip and a resilient tongued weather stripping member mounted between said flanges.

9. A window sash having a meeting rail comprising a hollow rectangular portion having a meeting face, a flange projecting from the inside edge of said face having an outwardly turned striking lip, a shoulder adjacent to the face of said flange, and a short rib formed on said rail having a marginal lip facing the lip on said inside flange.

10. In a pivoted window construction, a jamb and a sash rail, a pivot joining said jamb and said rail, said jamb and said rail having cooperating sealing and striking portions oppositely disposed on either side of said pivot, V-shaped resilient metallic weather strips mounted in said jamb, cooperating flanges on said rails engaging a leg of said V with increasing pressure as the window is closed, the vertices of said V-shaped weather strips pointing in opposite directions at opposite sides of said pivot.

11. In a window construction, a frame and a sash, said frame including a sill, said sash including a cooperating lower sash rail, said sill including an inwardly extending upwardly stepped portion terminating in an upwardly extending flange, said rail including a downwardly extending outside flange terminating in an inwardly turned lip, said inside flange being adapted to engage on the inside of said upwardly extending flange of said sill and said inwardly turned lip of said outside downwardly extend-

ing flange being adapted to engage against the riser of said stepped portion.

12. In a window construction, a pair of cooperating members adapted to meet and seal a window opening, one of said members having a flat base, a flange extending from the inner edge thereof terminating in an outwardly turned lip and a rib on the outer edge thereof and the other of said members including a base, a rib extending from the inner edge of said base terminating in an outwardly turned lip and a flange on the outer side of said member terminating in an inwardly turned lip, a resilient metallic weather strip held to said outwardly turned lip and said inwardly turned lip of said rib and said flange respectively of said second mentioned cooperating member, said outwardly extending flange of said first mentioned cooperating member being adapted to provide the first point of sealing contact with said second mentioned member, said rib of said first mentioned member and said resilient weather strip being adapted to provide the second point of contact and said inwardly turned lip of said outer flange on said second mentioned member and said rib on said first mentioned member being adapted to provide a third point of sealing contact.

13. In a swinging window having a frame, a sash including a tubular extruded non-ferrous rail, said rail having a narrow inside striking flange and wide outside striking flange, and a

stay, one end of which is pivoted to the frame, the improvement which consists in providing a slot in said rail, pivoting the other end of said stay through said slot to a sliding friction shoe 5 mounted within said hollow sash rail the bearing surfaces of said shoe acting against the inner surfaces of said hollow sash rail and cutting away said narrow inside striking flange of said rail to permit the placement of the stay between the sash rail and the frame when the window is closed.

14. In a window construction having a fixed frame member and a sash pivoted to swing on an axis parallel to and adjacent to a sash rail, an 15 outwardly progressive stepped portion on said frame member terminating at its inner extremity in an inside flange in a plane substantially parallel to the plane of said window, said sash rail including an outside wide flange terminating in an inwardly turned lip which engages the riser of one of said stepped portions of said frame, and an inside flange which engages the inside surface of said inside flange of said frame member and a resilient tongued metal weather strip 20 mounted between said flanges of said sash but outwardly of said inside flange leaving space for the seating of said inside flange of said frame when said window is closed.
